UNITED STATES PATENT OFFICE.

WILLIAM BARTHOLOMAE, OF NEW YORK, N. Y., ASSIGNOR TO BAR-ZIM TOY MANUFACTURING CO., INC., OF NEW YORK, N. Y., A CORPORATION OF NEW YORK.

MUSICAL INSTRUMENT.

Application filed May 1, 1922. Serial No. 557,767.

To all whom it may concern:

Be it known that I, WILLIAM BARTHOLOMAE, a citizen of the United States, and a resident of the city of New York, borough of Manhattan, in the county and State of New York, have invented a new and Improved Musical Instrument, of which the following is a full, clear, and exact description.

10 This invention relates to musical instruments and particularly to an improved instrument using tubes as the sounding members, the arrangement being such that either a striking hammer may be used for producing the desired sound or substantially an ordinary keyboard with an action associated therewith.

20 The object of the invention is to provide an improved construction of musical instrument using tubes which is simple in design with a minimum number of parts for securing the desired result.

25 Another object of the invention is to provide a piano action in connection with sound producing members.

A further object of the invention is to provide a single member piano action.

In the accompanying drawing—

30 Figure 1 is a top plan view of a musical instrument disclosing one embodiment of the invention.

Figure 2 is a sectional view through Figure 1 on line 2—2.

35 Figure 3 is a perspective view of one of the striking members or hammers of the piano action shown in Figure 1.

Figure 4 is a perspective view of a plate forming certain features of the invention.

40 Figure 5 is a perspective view showing a slightly modified construction of piano action and supporting member therefor.

Figure 6 is a perspective view of the instrument shown in Figure 1, but with the auxiliary keyboard removed.

45 Figure 7 is a perspective view of the keyboard or plate shown in Figure 6.

Referring to the accompanying drawing by numerals, 1 indicates a frame of wood or other desirable material provided with bars 2 and 3, said bars preferably diverging and accommodating sounding tubes 4. The construction and arrangement of bars 2 and 3, tubes 4 and the supports therefor are similar to the construction and arrangement shown 55 in my co-pending application, Serial No.

546,073 and, therefore, form no part of the present invention except in combination with certain other parts hereinafter fully described.

The frame 1 in addition to carrying the bars 2 and 3 carries a plate 5 preferably of wood which may act with certain other parts as a keyboard. Associated with this plate are end members 6 and 7 which hold in place a bar 8 on which are pivotally mounted a 65 number of swinging keys 9 shaped similar to an ordinary piano key except for the tubular section 10 surrounding the rod 8.

These keys are provided with suitable coloring matter to represent the white and 70 black keys of an ordinary piano keyboard and may be struck by the player to operate the piano action and thereby produce the desired music.

The piano action consists in providing a 75 number of striking hammers 11, each striking hammer being preferably of one piece and provided with an aperture 12 through which the rod 13 passes, said rod being secured to the ends of the frame 1 in any desired manner. Each of the hammers 11 is provided with a striking end 14, a curved body 15 and a finger engaging projection 16. When the various hammers are in proper position, the projection 16 extends 80 through the respective slot 17 in plate 5 and by reason of the weight of the body 15 and the end 14, the hammers assume under the action of gravity, the position shown in Figure 2 with the front portion of the extension 16 resting against the cord or cushion 18. The plate 5 acts as a bumping board, and particularly the various end walls 5'.

From Figures 2 and 6 it will be observed that the projection 16 on its return stroke 95 will strike against the respective walls 5', which therefore act as stops for the keys or hammers on their rebound motion. Usually this plate is made from wood and consequently will produce a sound or thumping 100 action. In order to cushion or deaden this thumping action a cushioning member is arranged adjacent each of the walls 5' and in position to be struck by the extension 16 on the rebound of the hammers 11. This 105 cushioning member is the cord 18 extending through the groove 19 formed in the plate 5. After the striking hammers have been properly arranged and the plate 5 also properly arranged as shown in Figures 1 110

and 2, the instrument is ready for use and the swinging keys 9 may be used as an ordinary keyboard of a piano. If desired, these keys could be removed and the fingers of the operator caused to strike the projections 16. When the device is used in this manner, the fingers of the operator will cause a proper action of the striking hammers 11 but will not move down into the slots 17 10 as they are too narrow.

When the upper end of the projection 16 is flush with the upper surface of the plate 5, the striking end 14 is not engaging the tube 4, but is a short distance therebelow. 15 By reason of this structure, it requires a blow on the hammers 11 to cause them to strike the tube 4. This construction permits the use of a single striking hammer and at the same time produces a proper hammer blow for securing the desired sound on the tube 4. If the hammers 11 remain in contact with the tube for striking, even for a short time, it would deaden the sound.

In Figure 5 a slightly modified structure 25 of hammer 11 is shown. In this construction a notch 20 is provided instead of the opening 12 whereby the hammer may rest upon a bar 21 secured to the frame 1 in any desired manner, said bar being preferably 30 a rectangular member which is comparatively thin whereby a minimum weight is provided and yet a maximum strength for long instruments. If desired, the upper edge of the supporting bar 21 could be 35 rounded in order to provide an easy pivotal action of the hammers 11.

What I claim is:—

1. In a musical instrument of the character described, a piano action provided with 40 a plurality of striking hammers, means for pivotally supporting said hammers, and a plate for limiting the movement of the operator when striking said striking hammers, said plate having a notch or opening for 45 each of said hammers, part of said hammers fitting in said notches and projecting above the same.

2. In a musical instrument provided with 50 a plurality of sounding members, a plurality of striking hammers for actuating said sounding members, means for pivotally supporting said hammers near one end, a plate for limiting said swinging movement in one direction, said hammers extending through

said plate, and co-acting therewith to form 55 a keyboard and cushioning means acting as a bumper for each of the hammers for limiting the swinging movement of the hammers through the plate.

3. In a musical instrument of the character described, a plurality of sound producing members, an action co-acting with said members formed with a supporting bar, and a plurality of striking hammers pivotally mounted on the supporting bar, and a 60 plate formed with apertures through which part of each of the hammers projects whereby when an operator plays the instrument the fingers of the operator may strike the 65 ends of the hammers extending through said 70 slots but cannot follow said hammers beyond said plate.

4. In a musical instrument of the character described, a plurality of sound producing members, an action therefor including a supporting rod and a striking hammer for each of said members, each of said striking hammers having an aperture for 75 accommodating part of said supporting rod, an apertured plate for receiving one end of 80 each of the hammers, said end projecting a short distance through the plate, and a cord extending the full length of said plate and acting as a bumper for each of the hammers.

5. In a musical instrument of the character described, a plurality of sounding members, a pivotally mounted one piece hammer for each of the respective sounding members, and a plate having openings 90 through which part of the respective hammers project whereby when an operator strikes the projecting part of said hammers the operator's fingers cannot follow the pivotally mounted hammers beyond said plate. 95

6. In a musical instrument of the character described, a plurality of sounding members, a pivotally mounted hammer for each of said sounding members, a stop plate having an aperture through which part of 100 one end of each of the hammers projects, said plate having a series of aligned notches therein, and a cushioning cord arranged in 105 said aligned notches, said cord being positioned so as to be engaged by said hammers when moving to the extreme position in one direction.

WILLIAM BARTHOLOMAE.
